HIGH POWER TUBE SUPPORT AND COOLING SYSTEM

Louis A. Gebhard, Washington, D. C., Edwin Lee White, Honolulu, Territory of Hawaii, and Corrie F. Rudolph, Washington, D. C., assignors, by mesne assignments, to Wired Radio, Inc., New York, N. Y., a corporation of Delaware.

Application June 17, 1926, Serial No. 116,591
Renewed February 13, 1929

3 Claims. (Cl. 250—27.5)

Our invention relates broadly to electron tube apparatus and more particularly to a resilient support and cooling jacket for high powered electron tubes.

5 One of the objects of our invention is to provide a construction of cooling jacket for high powered electron tubes by which a high powered tube may be readily centered within the cooling jacket and cooling fluid circulated around the anode of the 10 tube while shock vibration is prevented from reaching the electron tube structure by means of a resilient suspension interposed between a frame support and the electron tube.

Another object of our invention is to provide a 15 construction of socket support for a high powered electron tube wherein a liquid tight seal is provided, permitting the circulation of a cooling fluid around the anode structure of the electron tube at the same time supporting the tube and reducing 20 the transfer of shocks and jars to the electrodes of the tube structure.

Still another object of our invention is to provide a construction of high powered electron tube support and cooler therefor, wherein the anode 25 of an electron tube may be received and enclosed, and a liquid tight seal provided therewith in such manner that a cooling fluid may be circulated around the anode while the entire tube structure is suspended resiliently for preventing the transfer 30 of shocks and jars to the electrodes thereof.

Another object of our invention is to provide a 35 resilient support for a high powered electron tube structure, wherein a cylindrical receptacle is resiliently suspended from a frame structure for receiving the anode of a high powered tube with an annular hand grip for clamping the electron tube within the support and providing an electrostatic shield around the tube.

Other and further objects of our invention will 40 be understood from the specification hereinafter following by reference to the accompanying drawing wherein:

Figure 1 is a vertical cross-sectional view 45 through the shock proof mounting and cooling jacket for electron tubes, showing a high powered electron tube supported therein; and Fig. 2 is a fragmentary cross-sectional view through the electron tube mounting taken on line 2—2 of Fig. 1 and showing the outlet for the cooling fluid 50 which passes around the anode of the tube structure.

Referring to Fig. 1 this device consists of a 55 framework 1 with attached rings 2 and 3 forming a seat for two helical springs 4 and 5. The springs 4 and 5 serve to center the tube socket

in its mounting and provide an exceedingly long, flexible mechanical connection between the tube socket and frame which effectively absorbs all external vibrations. Straps 6 assist in supporting rings 2 and 3 and also act as abutments 60 against twisting movement of studs 7 which project between the straps 6. The jacket is provided with a screw clamping member 8 which serves to clamp the tube 9 against a gasket 10 and thus provide a watertight connection around 65 the neck of the tube. This member is also designed to provide a convenient hand grip and electrostatic shield around the tube. Part 8 is provided with movable slides 11 arranged to slide along guides 12 and engage the ledge 13 around 70 the anode of the vacuum tube 9. After the slides 11 have passed over the ledge 13 the screw clamping member 8 may be screwed down at 14 to form the watertight connection about the neck of the tube. 15 is a metal tube which is fastened to 75 part 16 at one end and part 17 at the other end. To part 17 is attached a connection 18 for the water or other liquid supply. Part 17 also provides a seat in the form of an annular ring 19 for spring 5. Part 16 provides a seat for spring 4 80 as represented at 20. It also provides a chamber 21 for circulation of cooling fluid which passes around the gap 22. The chamber 16 has attached to the outside thereof a thin metal ribbon 23 which provides good electrical connection 85 particularly at high frequencies, between the vacuum tube anode 24 and the external circuit. The ribbon 23 is looped to form a flexible mechanical connection and thus external vibrations are not transmitted to the tube. The other end of 90 ribbon 23 is fastened to the framework 1. Screws 26 serve to hold the anode 24 in alignment with the wall of metal tube 15 and thus provide a path for the flow of the cooling liquid which circulates about the anode 24. Screws 26 are held 95 by part 7, which is in turn fastened to 15. A part 27 serves to lock screw 26 in place. Part 28 is a resilient sleeving which provides a shock 100 proof covering for the parts 26, 7 and 27 which serve also as stops, or bumpers, limiting the motion of the whole unit when part 8 is put in place or removed. The stops are so situated that in normal operation they are a short distance from parts 6 for preventing the transmission of mechanical vibration to the vacuum tube. When 105 part 8 is loosened or tightened, the stops prevent movement beyond the short space between them and the framework 1 and parts 2 and 3. The jacket as a whole, is supported thru the framework 1 from insulators 25.

Heretofore in the art previous devices have been unsuitable for various reasons; principally (1) boiling of cooling liquid immediately about the anode of the tube, (2) improper shock-proof 5 mounting, and (3) excessive size.

The boiling of the cooling liquid about the anode of the vacuum tube is due to too low a velocity of flow of the water particularly at critical points. The improved jacket provides a small 10 opening 22 between the wall of the jacket 15 and the anode 24. This is important from an economical standpoint, lowering cooling liquid consumption. A narrow opening is suitable because due to the high velocity only the water immediately 15 in contact with the anode is effective in cooling. Particular difficulty has been experienced in previous designs at the neck of the tube. The improved jacket is provided with an opening 22 which is unobstructed about the entire tube 20 and thus leaves no unprotected parts. The liquid may flow up thru 18 about anode 24 and uninterrupted thru opening 22 to chamber 21. Chamber 21 has a larger cross-section than other 25 parts of the system and thus provides a low resistance path for the flow of the liquid from any point of opening 22. Chamber 21 has an outlet 29 on the opposite side of the view shown in Fig. 1, as shown more clearly in Fig. 2. A chamber 30 is provided to permit different lengths of 30 anodes 24 to be used and also to provide a small reservoir for the cooling liquid.

The shock-proof mounting of the improved jacket is arranged in such a way that mechanical vibrations from external sources are not 35 transmitted to the tube. This is done by arranging a maximum length of path of vibration with suitable rigidity. The arrangement is such as to provide a minimum of space and greatest compactness. This is highly desirable, particularly 40 at high frequencies. For satisfactory operation at these high frequencies, it is desirable to have minimum distributed capacities of associated circuit parts. To make these capacities low the parts must be as small as practicable. The improved jacket meets these requirements.

We have shown the spring members 4 and 5 as substantially conical in shape, that is, smaller 50 at their extreme outer ends and larger adjacent the central supporting structure. It will be understood, however, that straight cylindrical springs may be employed between the members 3-16 and 2-19.

The construction of our improved electron tube 55 socket support and cooling system is particularly desirable from the viewpoint of inexpensive manufacture and production.

While we have described our invention in a preferred embodiment we desire that it be understood that modifications may be made and that no limitations upon the invention are intended other than are imposed by the scope of the appended claims.

What we claim as new and desire to secure by Letters Patent of the United States is as follows:

1. A support for a high power electron tube structure having a depending cylindrical anode comprising a receptacle for enclosing the anode of said electron tube structure, a pair of ring members located adjacent the center of said receptacle and supported from a frame structure, a pair of coiled spring members disposed between said ring members and said receptacle, a fluid inlet adjacent the lower end of said receptacle and a fluid outlet adjacent the opposite end of said receptacle whereby cooling fluid may be circulated around said anode and mechanical vibration prevented from reaching said electron tube structure.

2. A support for a high power electron tube having a depending cylindrical anode comprising a receptacle adapted to receive the anode of said electron tube, a ring member adjacent the upper end of said receptacle for providing a sealing zone between said receptacle and said electron tube, means for circulating the cooling fluid from the lower portion of said receptacle around said anode and discharging the fluid adjacent the upper portion of said receptacle, a frame structure and a pair of coiled spring members disposed between said frame structure and said receptacle for suspending said electron tube structure resiliently during the circulation of cooling fluid around said anode.

3. A support for a high power electron tube having an elongated cylindrical anode comprising a cylindrical receptacle for receiving the cylindrical anode of said electron tube, spring supporting means for resiliently suspending said receptacle, a pair of ring members arranged to carry said spring supporting means, a supporting structure for permanently locating said ring members centrally of said receptacle, and a plurality of strip-like members extending longitudinally between said ring members and spaced one from another, a plurality of radially positioned stops secured to said receptacle and extending between said strip like members whereby twisting of said receptacle in said resilient suspension beyond definite limits is prevented.
